(57) CLAIM

The ornamental design for a medical ultrasound equipment, as shown and described.

DESCRIPTION

FIG. 1 is a first perspective view of a medical ultrasound equipment;

FIG. 2 is a second perspective view thereof;

FIG. 3 is a front view thereof;

FIG. 4 is a left side view thereof;

FIG. 5 is a right side view thereof; and,

FIG. 6 is a top view thereof.

The alternating dot and dash lines represent the bounds of the claim, and all other broken lines are included for the purpose of illustrating unclaimed portions of the medical ultrasound equipment. None of the broken lines form a part of the claimed design.

1 Claim, 6 Drawing Sheets
